ATTORNEY.

mediately adjacent to, the inside wall of the annular neck 12 of the extension 2 of the electron tube vessel. The electrostatic shield of my invention is represented at 16 in the form of a 5 tubular member which extends throughout the length of the grid conductor 11. The tubular shield 16 has a downwardly depending portion 18 illustrated more clearly in Fig. 4 which is slotted as shown at 17 adapted to resiliently engage the 10 upper extension 2 of the electron tube.

As illustrated in Fig. 4, the depending portion 18 of the electrostatic shield 16 has an annular neck 19 adapted to engage the annular neck 12 on the upper extension 2 of the electron tube.

15 The contour of the tubular shield is such that the flexible grid lead may be disposed axially thereof and insulatingly supported away from the interior walls of the shield by suitable means such as insulator 20. It will be seen that there is 20 electrically continuous shielding for the grid electrode 7, the supporting frames 8 and the grid lead 11. That is there is no electrical gap intermediate the end of the control grid 7 and some portion of the tube structure for the threading of 25 lines of force and the introduction of retroactive effects.

The arrangement of the tube structure of my invention in a power amplifier system has been 30 shown more clearly in Fig. 2. In this circuit an oscillator has been illustrated at 21 arranged within a shielded cabinet structure indicated at 22. The oscillator is shown controlled by a piezo electric crystal element 23 and as having an oscillatory circuit 24 associated therewith. The 35 power amplifier stages are contained within the shielded compartments 25 and 26. An electrically conductive partition member 25a extends between shielded compartment 25 and shielded compartment 22. An electrically conductive partition member 26a extends between the compartment 26 and compartment 25. The circuits for the several power amplifier stages and the high frequency oscillator have been shown diagrammatically for the purpose of illustrating the 40 relationship of the shield to the screen grid electrode of the power amplifier tubes. The power amplifier tube 1 is shown having the tubular shield 16 extending through partition 25a and establishing electrical connection with the shield by means of the contact springs 27. The 45 capacity coupling between the shield 16 and the screen grid 14 has been indicated by the dotted line condenser 28. By observing the arrangement of the electrodes in the tube structure of Fig. 1, it will 50 be clearly apparent that the control grid and the lead connecting the control grid is wholly shielded throughout all parts thereof which are subject to coupling with associated parts of the tube or circuits connected thereto. For example the tuned output circuit 30 of the power 55 amplifier system is not subject to electrostatic or magnetic coupling with respect to the control grid by reason of the complete isolation of the control grid and grid lead by means of the shield 16. A similar arrangement is provided in 60 compartment 26 where electron tube 31 has its control grid and grid lead isolated from other parts of the tube circuit by means of the shield 16 mechanically connected with one end of the 65 evacuated vessel constituting the tube 31.

In high power installations I prefer to enlarge 70 the diameter of the tubular shield 16 to offer as little capacity with respect to the grid lead 75 as possible. I prefer to omit the insulation 20

and use a stiff conductor in place of flexible leads eliminating dielectric losses. When it is necessary to interchange the electron tubes, the shield for the grid lead may be readily removed by snapping the end thereof away from the annular neck 12 and removing the conductors 11 from the terminals at the end of the tube. When a replacement tube is inserted in place of the tube which is removed the connecting leads 11 are restored to the points of connection on the tube and the shield again snapped into position thereby completing the electrostatic shield- 85

ing for the tube system.

The complete isolation of the control grid and its leads from the plate circuit prevents feedback 90 of energy from the plate to the grid and renders the amplification of the oscillator highly stable, thus increasing the efficiency of the operation of the amplification system.

While I have described my invention in one 95 of its preferred embodiments I desire that it be understood that modifications may be made and that no limitations upon my invention are intended other than are imposed by the scope of the appended claims.

What I claim as new and desire to secure by Letters Patent of the United States is as follows:

1. An electron tube comprising an evacuated vessel having a projecting tubular portion, an annular neck of reduced cross-section 105 disposed along said tubular portion, a multiplicity of electrodes disposed within said vessel, one of said electrodes constituting a screen grid, and a conductive shield encircling the tubular portion of said evacuated vessel and engaging the annular neck thereof and establishing electrical coupling to said screen grid.

2. An electron tube comprising an evacuated vessel having a tubular extension thereon, a multiplicity of electrodes disposed within said vessel, 115 one of said electrodes constituting a control grid having a supporting member extending through the tubular extension of said vessel and another of said electrodes comprising a screen grid encircling said control grid and extending interiorly 120 of the tubular portion of said evacuated vessel, an annular neck of reduced cross-section in the tubular portion of said evacuated vessel, and an electrostatic shield encircling the exterior of the tubular portion of said evacuated vessel and engaging the annular neck thereof in capacitative 125 relation to the shield grid interiorly of said vessel.

3. An electron tube comprising an evacuated vessel having a tubular extension thereon, a multiplicity of electrodes within said vessel including 130 a control grid, a frame structure supporting said control grid and extending into the tubular extension of said evacuated vessel, an independent frame structure surrounding said aforesaid frame structure, a screen grid carried by said independent frame structure, an annular neck of reduced cross-section in said tubular extension and a conductive shield engaging the annular neck in said tubular extension in capacitative relation to the 135 screen grid interiorly of said evacuated vessel.

4. An electron tube device comprising an evacuated vessel, a tubular extension on said vessel, said tubular extension having an annular neck of reduced cross-section therein, a frame structure disposed axially of said evacuated vessel and projecting through said tubular extension and forming a terminal exteriorly thereof, a control grid carried by said frame structure, an independent frame structure concentrically dis- 145 150

posed about said aforementioned frame structure interiorly of said evacuated vessel and projecting into the tubular extension of said evacuated vessel, a screen grid carried by said independent frame structure, and extending into said tubular extension beyond said control grid and beyond the frame on which said control grid is mounted, an electrostatic shield engaging said annular neck of the tubular extension of said evacuated vessel in close capacitative relation to said shield grid for forming a continuous electrical shield for said control grid and the lead of said control grid. 80
